UNITED STATES PATENT OFFICE.

JOHN McRAVEN, OF LITTLE ROCK, ARKANSAS.

SAFETY THIRD RAIL FOR RAILWAY-TRACKS.

No. 846,339.

Specification of Letters Patent.

Patented March 5, 1907.

Application filed February 27, 1906. Serial No. 303,279.

To all whom it may concern:

Be it known that I, JOHN McRAVEN, a citizen of the United States, and a resident of Little Rock, Arkansas, have invented certain new and useful Improvements in Safety Third Rails for Railway-Tracks, of which the following is a specification containing a full, clear, and exact description, reference being had to the accompanying drawings, forming a part hereof.

My invention relates to a safety third rail for railway-tracks; and the object of my invention is to arrange a third rail or guard in the center of a railway-track and to arrange a grooved wheel upon the center of each of the car-axes, which grooved wheels engage upon the third rail, and thus prevent the derailment of the car-wheels as a result of spreading or broken rails.

To the above purposes my invention consists of certain novel features of construction and arrangement of parts, which will be hereinafter more fully set forth, pointed out in my claims, and illustrated in the accompanying drawings, in which—

Figure 1 is a perspective view of a section of my improved safety third rail. Fig. 2 is a transverse section through the rails of a railway-track with my safety third rail in position between the track-rails and the grooved wheel in position upon the car-axle. Fig. 3 is a vertical section taken on the line 3 3 of Fig. 2.

Referring by numerals to the accompanying drawings, 1 indicates the cross-tie, and 2 the ordinary track-rails, which are spiked to the cross-tie in the usual manner.

3 designates the car-axle, and 4 the car-wheels fixed to said axle and running upon the rails 2.

My improved safety third rail, which is located midway between the track-rails 2 and extends parallel therewith, is A shape in cross-section, with the inclined side portions 5, the lower ends of which are bent outwardly into horizontal planes to form flanges 6, which rest directly upon the cross-ties 1 and upon the edges of which the spikes are arranged which fix the third rail to the cross-ties. The upper ends of the side portions 5 extend vertically upward, as indicated by 8, which portions are parallel with each other and are united at their upper ends by the integral section 9, which is horizontally disposed. This third rail so constructed is very light in weight and owing to its peculiar

shape is very strong and can be easily manufactured.

Loosely mounted upon the center of the axle 3 is a grooved wheel 10, the periphery of which is immediately above but not in contact with the top surface of the upper end of the third rail, and integral with the sides of this wheel 10 are the flanges 11, the innerfaces 12 of which are beveled or formed on angles 65 corresponding to the inclined side sections 5 of the third rail. When the car-wheels 4 are on the track-rails 2, the flanges 11 on the lower side of the wheel extend downwardly over the upper portion of the third rail, and the space between said flanges is such that the side faces of the third rail do not bear against said flanges. The wheel 10 is held upon the axle 3 against lateral motion by means of the collars 13, which are locked 75 to said axle by the set-screws 14. As long as the car-wheels 4 ride in proper position upon the flat rails 2, the grooved wheel 10 travels over the upper portion of the third rail without engaging thereon; but should 80 the track-rails 2 spread or break, so as to allow one or both of the car-wheels 4 to drop or shift to either side, the upper portion of the third rail will be engaged by the wheel 10 and its flanges, and thus the car-wheels 85 will be carried in proper position past the spread or broken rails, and without accident to the car beneath which the wheels are arranged.

My improved safety-rail is applicable for 90 all car-tracks, is easily and quickly placed in position, and greatly reduces the liability of accidents due to spreading or broken rails.

The center rail is somewhat higher than the ordinary track-rails, and the grooved 95 wheel 10 is loose upon the car-axle, so that it can travel on top of the third rail when engaged thereon. The center rail may be discontinued through switches, as trains generally slacken speed while traveling onto or 100 past a switch.

I claim—

1. The combination with a rail arranged between the track-rails of a railway-track, and a grooved wheel loosely mounted on the 105 car-axle above said rail; substantially as specified.

2. The combination with an A-shaped rail positioned between the usual track-rails of a railway-track, of a grooved wheel 110 loosely mounted upon the car-axle, and which grooved wheel extends downwardly

over the top of the A-shaped rail; substantially as specified.

3. The combination with a car-axle, of a pair of collars rigidly held on the center thereof, a grooved wheel arranged for rotation on the car-axle between said collars, and an A-shaped third rail fixed to the ties between the ordinary track-rails, and the upper end of said third rail extending between the

flanges of the wheel; substantially as specified.

In testimony whereof I have signed my name to this specification in presence of two subscribing witnesses.

JOHN McRAVEN.

Witnesses:

M. P. SMITH,

JOHN C. HIGDON.
